TAMPON

Joseph R. Crockford, Mount Rainier, Md., assignor to Harry Radzinsky and Sidney W. Dean, Jr., both of New York, N. Y.

Application October 19, 1943, Serial No. 506,811

5 Claims. (Cl. 128—270)

1

This invention relates to tampons and particularly to the type employed for menstrual purposes.

One of the objects of the invention is to provide an article of this character which will be soft, highly absorbent, and capable of expanding to fill the vaginal cavity without the imposition of undue pressure on the cavity wall, and which may be speedily and economically manufactured in quantity from readily-available materials.

Another object of the invention is to provide a tampon of this character which may be wholly constructed from absorbent cotton or other similar soft and fibrous material; which may be folded and compacted and contained within a tubular applicator, and which when released from the applicator will tend to expand and adapt itself to the shape of the vaginal cavity, not only serving to hold its position therein but to effectively prevent the passage or leakage of menstrual fluid.

The invention also contemplates an arrangement of parts of the tampon whereby the fibres of the absorbent material employed are effectively held together to prevent "shredding" of the tampon, and in addition, the pull string used is securely anchored to the body of the tampon.

The invention further contemplates a laminated arrangement of certain plies or layers of the body of the tampon whereby said body is greatly strengthened; the fibres are strongly held together and the tampon as a whole is rendered more effective for the purpose intended.

Another feature of the invention resides in the manner in which the body of the tampon is folded into substantially S shape and is compacted and placed, while in such folded and compacted condition, within a tubular applicator.

In the accompanying drawing, in which an embodiment of the invention is shown, Fig. 1 is a face view of a tampon constructed in accordance with the invention, the tampon being shown in its open or unfolded condition; Fig. 2 is a top view of the open tampon; Fig. 3 is a sectional view on the line 3—3 of Fig. 1, looking in the direction of the arrows; Fig. 4 is a top view of the tampon, showing how it is folded preparatory to being compacted for placement in an applicator; Fig. 5 is a side view of the structure of Fig. 4; Fig. 6 is a sectional view on the line 6—6 of Fig. 2, looking in the direction of the arrows, and Fig. 7 is an end view of an applicator with the folded and compacted tampon contained within it.

The main layer, herein referred to as the "body" or body layer, is indicated at 1 and the same consists of a substantially rectangular piece

5 of thick, soft and absorbent fibrous material, such as for example, absorbent cotton. This piece of such material is so cut that its fibres 2 extend in the same direction, or transversely of the length of the piece as clearly seen in Figs. 1 to 3. Extending around at least one end of the body layer 1 and over the two faces of the body layer, is a reinforcing strip 3, which is preferably, but not necessarily, made also of a soft, absorbent material such as cotton, or in other words, a material similar to or having the same characteristics as that of which the body layer 1 is composed. It will be noted however, that the fibres 4 of the strip 3 extend substantially at right angles to those in the layer 1. That is to say, the fibres 4 of the strip 3 extend longitudinally of the strip and transversely to the fibres in the layer 1.

The result of this arrangement is that the central portion of the tampon is laminated by several layers in which the fibres in at least one layer are disposed at right angles to those in the other layers. Through this laminated central part of the tampon is placed at least one line of stitching 5, extending for the length of the strip 3 and serving to tie the several layers together. At one end, the thread or cord which forms the stitching 5, is continued beyond the end of the tampon, as indicated at 6, to constitute a free end or pull string by means of which the tampon may be

30 withdrawn from the body orifice. It will be observed that the reinforcing strip 3 is much narrower than the body layer 1, with the result that the opposite ends of the layer 1 and which are respectively designated at 7 and 8, project beyond the opposite longitudinal edges of the reinforcing piece 3. To place the tampon into the conventional tubular applicator, such as is shown at 10 in Fig. 7, the ends 7 and 8 are folded back in opposite directions so that they overlie the central strip 3. This will be clearly seen in Fig. 4 wherein it will be noted that the end 7 has been folded forwardly to overlie the front face of the strip 3, while the end 8 has been folded rearwardly to overlie the back ply of the strip 3. As a result, the tampon assumes an S-shape, and after having been folded into such shape, it is then compacted to fit within the applicator 10. The manner in which the compacted tampon fits within and fills the interior of the applicator 10 will be clearly seen in Fig. 7.

When the tampon is ejected from the applicator into the vaginal tract, the natural tendency of the oppositely-folded ends 7 and 8 is to straighten out, and this tendency causes spreading or expansion of the body of the tampon, so that it

adapts itself readily to the internal shape of the orifice and not only retains itself in place therein, but closely fits the orifice and prevents leakage.

The folding of the body of the tampon in the manner explained enables a tampon of considerable size to be compacted into a relatively small applicator, thereby not only facilitating insertion, but providing a tampon of ample size to effectively perform its intended function.

The arrangement of the several layers or plies with the fibres thereof at right angles to each other, and the stitching extended through said plies, causes the body of the tampon to be firmly held together; excessive shredding of the fibres is prevented and disintegration while saturated is unlikely.

By the structure described, a tampon may be made which is wholly composed of soft, fluffy and compressible cotton, thus being highly absorbent. The reinforced central portion of the tampon, actually constituting a core for the tampon, is, by folding of the body of the tampon in the manner described, substantially enclosed in and surrounded by the soft, fluffy ends 7 and 8 of the body layer, so that a soft body is provided which may be used with ease and comfort and which will assure full protection.

While I have herein set forth the fact that the several layers or plies constituting the body of the tampon are preferably made of absorbent cotton, it will be understood that other materials might be effectively used.

What I claim is:

1. A tampon comprising a piece of soft and absorbent material having a narrow strip secured across at least one of its faces, the side edge portions of the piece extending beyond the edges of the strip, one of the edges of the piece being folded to overlie a face of the strip, and the other edge of the piece being folded in a reverse direction, whereby the piece assumes a substantially S-shape.

2. A tampon composed of a layer of soft and absorbent material having fibres extending in the same direction, a reinforcing piece of less width than the layer and composed of soft absorbent material extending across the layer and having its fibres at an angle to those of the layer and constituting a core for the layer, the layer being

folded into substantially S-shape and having its folds extending substantially parallel to the axis of the tampon, and a tubular applicator in which the tampon is contained and maintained in said S-shape.

3. A tampon comprising, a piece of soft and absorbent material of fibrous nature, said piece having its fibres extending in substantially the same direction, a reinforcing strip also of soft and absorbent material extending over the opposite faces of the piece and also extending around one end of the piece, the fibres of the strip being disposed angularly with respect to those of the piece, stitching for securing the strip and piece together, the strip being narrower than the piece whereby side portions of the piece project beyond the edges of the strip, said projecting side portions being folded in opposite directions whereby one of them overlies the portion of the strip that is disposed on one side of the piece and the other portion overlies the part of the strip that is located on the opposite face of the piece.

4. A tampon consisting of a substantially rectangular body of thick absorbent fibrous material such as cotton, the fibres of said body all extending in substantially the same direction, a reinforcing strip having fibres extending at right angles to those of the body, said strip overlying parts of opposite faces of the body and being stitched thereto, the body being folded longitudinally so that one folded part extends over the strip on one face of the body, and another folded part extends over the strip on the opposite face of the body whereby the strip is disposed between said folded parts and forms the core of the tampon.

5. A tampon comprising a piece of soft and absorbent material having its central axis reinforced, the side edge portions of the piece extending beyond the sides of the reinforcement, one of the edge portions of the piece being folded in one direction on a fold line extending substantially parallel to the reinforcement and to the axis of the piece, and the other edge portion of the piece being folded in a reverse direction, whereby the piece assumes a substantially S-shape.

JOSEPH R. CROCKFORD.
